UNITED STATES PATENT OFFICE.

NATHAN D. INGRAM, OF HOLYOKE, MASSACHUSETTS.

DESIGN FOR A PENCIL-HOLDER.

SPECIFICATION forming part of Design No. 28,559, dated May 10, 1898.

Application filed March 30, 1898. Serial No. 675,807. Term of patent 14 years.

To all whom it may concern:

Be it known that I, NATHAN D. INGRAM, a citizen of the United States of America, residing at Holyoke, in the county of Hampden and State of Massachusetts, have invented and produced a new and original Design for a Pencil Case or Holder, of which the following is a specification, reference being had to the accompanying drawings, forming part thereof.

Figure 1 is a perspective view of one side of a pencil-holder showing my new design. Fig. 2 is also a perspective view of the pencil-holder, showing the opposite side to that shown in Fig. 1.

As shown in the drawings, the leading feature of the pencil-holder consists in a tubular body *a*, of cylindrical form, having a narrow opening *b* therein extending from end to end of said body in a line parallel with the axis thereof. Said opening *b* at one end thereof is widened slightly, as at *a'*.

Referring now to Fig. 2, it is seen that diametrically opposite to the widened part *a'* of the opening *b* (shown in Fig. 1) is located the opening *a²*, whose dimensions coincide substantially with those of the opening *a'*, and the narrowed-down portions *d* of said body *a* resulting from the location of the said openings *a'* and *a²* have their ends rounded, as shown, and at a point substantially concentric with said rounded ends are the circular openings *f*, axially in line one with the other.

Having thus described my invention, what I claim is—

The design for a pencil-holder, substantially as herein described and shown.

NATHAN D. INGRAM.
